ATTORNEY

UNITED STATES PATENT OFFICE.

GOTTHOLD LANGER, OF TRENTON, MISSOURI, ASSIGNOR OF ONE-HALF TO
HENRY F. HOFFMAN, OF SAME PLACE.

AUTOMATIC SMOKE-CONSUMER.

SPECIFICATION forming part of Letters Patent No. 438,005, dated October 7, 1890.

Application filed January 24, 1890. Serial No. 338,033. (No model.)

To all whom it may concern:

Be it known that I, GOTTHOLD LANGER, a citizen of the United States, residing at Trenton, in the county of Grundy and State of Missouri, have invented certain new and useful improvements in admitting air above the fire to furnaces and fire-boxes of steam-boilers for the purpose of preventing the accumulation of dense black smoke, of which the following is a specification.

Heretofore smoke has been prevented by admitting a certain per cent. of air above the fire through pipes or tubes set in and made solid in the sides of fire-boxes and furnaces; but said pipes and tubes standing open permanently result in a great loss of heat or evaporating power of the boiler and thereby increasing the expense of fuel for heating such furnaces or fire-boxes.

My invention is to prevent the accumulation and escape of dense black smoke by admitting air through pipes and tubes above the fire to furnaces and fire-boxes of steam-boilers and to shut off the air automatically without the attention of engineer or fireman after it has accomplished its purpose, (of preventing the accumulation and escape of dense black smoke,) so as not to cool unnecessarily the interior of such furnaces and fire-boxes as to result in a loss of heat or evaporating-power of the boiler. I attain these objects by the mechanism illustrated in the accompanying drawing, in which the figure is an end elevation of a steam-boiler and furnace provided with my improvement.

In the construction shown the globe-valve *a* admits and shuts off the steam when necessary. After there is sufficient steam-pressure in the boiler to admit the working of my invention the globe-valve *a* is left open. The rod *b*, which passes through the hinges of the fire-door and is made fast thereto by means of pins, is extended and used as a valve-stem, having a steam-tight valve attached to its lower end within the valve-casing *c*. By opening the fire-door the rod *b* will have to turn in its bearings, and in so doing will turn the valve within the valve-casing *c*. This movement will allow the steam to rush into the steam-cylinder *d* and push the piston made fast to

the piston-rod *n* in the direction of the shaft *m*. (Represented at the left side of the drawing.)

The cylinder *d* has a hole in one end (the left end in the drawing) just large enough to permit the easy movement of the piston-rod *n* and to hold the piston-rod *n* firmly in the center of the cylinder *d*. The other end of the cylinder *d* (the end nearest the right side of the drawing) is made steam-tight with packing in the stuffing-box *e*.

The piston-rod *n* also passes through the stuffing-box *e*, and is made long enough to admit the compression of the spiral spring *f* to give it sufficient power of extension to force the piston-rod *n* back to the point of starting. The piston-rod *n* has threads cut on it for a distance to allow the nut *g* to be screwed against the spiral spring *f* to adjust it according to the time the air tubes or pipes are required to be left open. The piston-rod *n* is fastened at both ends to connecting-rods, as *o*, and levers forged or cast on the shaft *m*.

The top of the shaft *m* has levers also, which are fastened to connecting-rods, similar to *o*, which are connected with a slide *h*, which is held by the gibbs *k* and *k'* to the bottom plate *i*, which can be seen through the holes in the sliding plate *h*. This bottom plate *i* is fastened directly to the sides of the furnace or fire-box. The bottom plate *i* and also the slide *h* have holes drilled through them at equal distances from center to center, so that when the slide *h* moves on the bottom plate *i* it will either open or close the holes in the bottom plate *i*. The tubes or pipes leading into the inside of the furnace or fire-box are the same distances from each other from center to center as the holes in the bottom plates and slides, so that when the plates *i* are fastened over the tubes or pipes the openings in the tubes or pipes shall correspond to the holes in the plates and slides.

As the slide *h* is connected by connecting-rods, like *o*, to the shaft *m*, and the shaft *m* is connected by its levers and connecting-rods with the piston-rod *n*, it follows that the movement of the slides, like *h*, is dependent upon the motion of the piston-rod *n*. Further, as the opening of the fire-door causes

the steam to rush into the steam-cylinder *d* and move the piston-rod *n*, this movement will also cause the slides, like *h*, to move and open all the tubes covered by the slides and 5 allow the air to pass into the fire-box.

The closing of the fire-door shuts off the steam, except the quantity of steam already in the cylinder *d*. This steam in the cylinder *d* will gradually condense, and thereby weaken 10 the resistance which causes the compression of the spiral spring *f*. The spiral spring *f* will gradually overcome the resistance of the condensing steam, and by its power of extension will push the piston-rod *n* and all its 15 connections and slide back to their former positions as before opening the fire-door.

Other slides, which can be seen in the drawings, are connected to the sides of the boiler. The number of these slides depends upon the 20 number of air-tubes to be inserted in the boiler.

The length of time for the tubes to be left open can be regulated by the nut *g*, which will increase or lessen the resistance of the spiral 25 spring *f*, and thereby shorten or lengthen the stroke of the piston-rod *n* and all slides connected thereto and controlled thereby.

In the bottom of the steam-cylinder *d* is a valve *x* on one end of the steam-cylinder *d*, and 30 under the other end of the steam-cylinder *d* is a drain-pipe to drain off the water confined in the steam-cylinder *d* and created by the condensing of the steam.

The valve *x* is intended to open by the 35 pressure of the atmosphere or air when the condensing of the steam has produced a vacuum inside the cylinder *d*.

Both drain-pipes may be united at *p*, as in the drawings, and then lead out of the boiler 40 by a single pipe.

What I claim as my invention, and desire to secure by Letters Patent, is—

1. In an apparatus, substantially as described, the combination of the furnace, the 45 devices for admitting air to said furnace, steam-operated devices by which to actuate the air-inlet devices, a valve by which to control the supply of steam to the steam-operated devices, the furnace-door, and connections between the said door and the steam-valve, whereby the said valve may be operated by the opening and closing of the furnace-door, all substantially as and for the 50 purposes set forth.

55 2. The combination of the furnace, its door and air-inlet devices, a steam-cylinder provided with a piston connected with and adapted to operate such air-inlet devices and hav-

ing its piston-rod extended and provided with an actuating-spring by which to operate said piston to close the air-inlet devices, the steam-supply devices leading to the said steam-cylinder and provided with a valve, and connections between said valve and the furnace-door, all substantially as and for the purposes 60 set forth.

3. The combination, in an apparatus, substantially as described, of the furnace, its door, the air-inlet devices, the steam-cylinder having its piston connected with and arranged to 70 operate said inlet devices, the steam-pipes, the valve-casing, and the valve operating therein and connected with the furnace-door, whereby it may be operated by the movements of said door, substantially as and for the purposes 75 set forth.

4. In an apparatus, substantially as described, the combination of the furnace, devices for admitting air thereto, steam-operated devices for operating said inlet devices, a valve 80 by which to control the supply of steam to the steam-operated devices, and a rod connected with and arranged to be turned by the opening and closing of the door, said rod being connected with and arranged to open and 85 close the valve, all substantially as and for the purposes set forth.

5. The combination, in an apparatus, substantially as described, of the furnace, its door, the air-inlet devices including the perforated 90 slides, the shafts having crank-arms connected with said slides and crank-arms for connection with the piston-rod, the cylinder, and piston, the latter having its rod connected with the crank-arms of the shafts, the valve controlling the admission of steam to the cylinder, and connections between said valve and the furnace-door, whereby the opening of the 95 door may operate the valve, substantially as set forth.

6. The combination of the furnace, its door, the air-inlet devices, the cylinder *d*, having its piston connected with the inlet devices to operate the same, the valve-casing *c*, a pipe connecting said casing with the cylinder *d*, the pipe connecting said casing with the boiler and provided with a throttle *a*, the valve in 100 said casing, the furnace-door, and the rod *b*, connecting said door with the valve in casing *c*, all substantially as and for the purposes 110 set forth.

GOTTHOLD LANGER.
